(57) **CLAIM**

The ornamental design for a combi oven with single plate and vertical window, as shown and described.

DESCRIPTION

FIG. 1 is a top, front, side perspective view of a combi oven with single plate and vertical window according to the present design;

FIG. 2 is a front view of the combi oven with single plate and vertical window of FIG. 1;

FIG. 3 is a rear view of the combi oven with single plate and vertical window of FIG. 1;

FIG. 4 is a right side view of the combi oven with single plate and vertical window of FIG. 1;

FIG. 5 is a left side view of the combi oven with single plate and vertical window of FIG. 1;

FIG. 6 is a top view of the combi oven with single plate and vertical window of FIG. 1; and,

FIG. 7 is a bottom view of the combi oven with single plate and vertical window of FIG. 1.

The broken line showing of FIGS. 1-7 is for the purpose of illustrating environmental structure and forms no part of the claimed design.
